UNITED STATES PATENT OFFICE.

WILLIAM A. INGLER, OF NEWARK, OHIO, ASSIGNOR TO HOLOPHANE GLASS CO. INC.,
OF NEW YORK, N. Y., A CORPORATION OF NEW JERSEY.

ILLUMINATING APPLIANCE

Application filed February 20, 1922. Serial No. 537,845.

To all whom it may concern:

Be it known that I, WILLIAM A. INGLER, a citizen of the United States, and a resident of Newark, in the county of Licking and State of Ohio, have invented certain new and useful Improvements in Illuminating Appliances, of which the following is a specification.

The object of this invention is to provide a lower closure for bowls, reflectors or the like used with lighting fixtures so that such units may be used in their original form as open-mouthed units, or else as closed units to conform to other conditions.

Fig. 1 is a vertical cross section of a globe showing the closure member inserted half-way therein and illustrative of the method in which such member is introduced.

Fig. 2 is a bottom plan view of an open-mouthed globe with the closure member in final position.

Fig. 3 is a fragmentary vertical cross section on line 3—3 of Fig. 2 at a point of contact where the closure member is furnished with a rim.

Fig. 4 is a fragmentary cross section of the wall of the globe of the closure member on line 4—4 of Fig. 2 at the points where the rim of the closure member has been taken away.

In many modern lighting installations it has been found that the use of a lighting unit having a closed bottom is most desirable. My device permits the closing of open-mouthed globes, reflectors or other envelopes now in use or permits the marketing of open-mouthed envelopes to be used with or without the bottom closure so that light can be directly emitted through the open

mouth of the enclosure or else it can be sealed in the manner hereinafter explained. In the figures 1 is a globe used in connection with lighting fixtures having a hollow portion 2 and walls 3. This type of envelope has been arbitrarily chosen as the invention can be used with any type of bowl or reflector where the lower or mouth opening has been left open. Such bowls or reflectors must have a reentrant edge at the

lower opening on which the closure member can rest. The invention consists in providing such opening 4 with a closure cap or member 5, distinguished by having a rim 6

which does not extend all the way around the cap but at points 7 and 7' opposite each other, the rim is omitted so that the closure can be introduced into the opening at the points where the rim is omitted and when the cap is so introduced it can be turned so that the mouth or rim of the globe 1 furnishes a secure seat or hold for the rim 6 of the cap. An ornamental tip 9 is here shown as placed on the cap, but this is not an essential part of my invention. The cap is easily removed by tipping it upwardly inside of the globe until the straight sides 7 and 7' come in contact with the mouth of the globe when the cap easily slides out in the position shown in Fig. 1. In the ordinary globe or reflector with sealed bottom, the entire closure must be removed to clean or take out the lamp, and the upper opening of such enclosure must be large enough to clear the greatest diameter of the lamp. A feature of the present invention is the fact that it is only necessary to remove the lower cap to take out the lamp, if the opening 4 in the globe be large enough, and it is assumed that when the unit is sold as a complete new product this will always be the case. It will be readily seen in such case that the upper opening shown at 2 in Fig. 1 may be made narrower than the maximum lamp diameter if so desired, because the lamp is removed by way of the lower opening.

The cap can be made of transparent or light diffusing glass or it may be made of metal and be absolutely opaque. The construction and principle is not affected by the material used either in the envelope itself or in the cap.

I claim:

A globe or reflector comprising an envelope having a lower opening, and a separate closure member with its perimeter partially curved and partially straight, the straight sides of the closure being adapted to enter the lower opening at an angle thereto, so as to permit the closure after complete entry to rest in the interior of the lower opening of the envelope to completely close the same.

Signed at Newark, in the county of Licking and State of Ohio, this 13th day of February, 1922.

WILLIAM A. INGLER. [L. S.]
